US0D1016746S

(12) **United States Design Patent** (10) Patent No.: **US D1,016,746 S**
(45) Date of Patent: ** Mar. 5, 2024

(54) **CHARGING CRADLE**

(71) Applicant: **Jiangyu Kangjian Innovation Medical Technology(Chengdu) Co., Ltd**,
Chengdu (CN)

(72) Inventors: **Chieh Kuo**, New Taipei (TW);
Ying-Wei Sheng, New Taipei (TW);
Ping-Hao Liu, New Taipei (TW)

(73) Assignee: **Jiangyu Kangjian Innovation Medical Technology(Chengdu) Co., Ltd**,
Chengdu (CN)

(**) Term: **15 Years**

(21) Appl. No.: **29/806,949**

(22) Filed: **Sep. 8, 2021**

(30) **Foreign Application Priority Data**

CLAIM

The ornamental design for a charging cradle, as shown and described.

DESCRIPTION

FIG. 1 is a front perspective view of a charging cradle, showing our design.

FIG. 2 is a bottom rear perspective view thereof.

FIG. 3 is a top plan view thereof.

FIG. 4 is a bottom plan view thereof.

FIG. 5 is a left side elevation view thereof.

FIG. 6 is a right side elevation view thereof.

FIG. 7 is a front elevation view thereof; and,

FIG. 8 is a rear elevation view thereof.

The broken lines shown in the drawings are included for purpose of illustrating portions of the charging cradle that form no part of the claimed design.

1 Claim, 8 Drawing Sheets
